BRACKET FOR A VEHICLE MIRROR SUPPORT

George E. Kilbey, 513 Sarah St., Mishawaka, Ind.

Filed Nov. 25, 1964, Ser. No. 82,792

Term of patent 14 years

(Cl. D14—6)

This is a continuation-in-part of application Serial No. D.75,282, filed June 10, 1963, and now abandoned.

I claim:

The ornamental design for a bracket for a vehicle mirror support, substantially as shown and described.
